UNITED STATES PATENT OFFICE.

ALFRED C. STEWART, OF LOS ANGELES, CALIFORNIA.

CARBURETER.

1,010,003.

Specification of Letters Patent. Patented Nov. 28, 1911.

Application filed November 1, 1909. Serial No. 525,819.

To all whom it may concern:

Be it known that I, ALFRED C. STEWART, a citizen of the United States, residing at Los Angeles, in the county of Los Angeles and State of California, have invented a new and useful Carbureter, of which the following is a specification.

This invention relates to carbureters for use with internal combustion engines, and its main object is to provide a carbureter in which the richness or proportion of fuel to air in the mixture, is increased rather than diminished when the throttle is nearly or quite closed so as to barely keep the engine running.

A further object of the invention is to provide for "flushing" the carbureter in starting.

Another object of the invention is to cause the gasoline to be rapidly evaporated and to keep it from spattering or collecting on the walls of the solid parts.

Other objects of the invention will appear hereinafter.

In the accompanying drawings illustrating the invention: Figure 1 is a vertical section of the carbureter in the plane of the air inlet. Fig. 2 is a vertical section transverse to Fig. 1. Fig. 3 is a horizontal section on line x^3-x^3 in Fig. 2. Fig. 4 is a horizontal section on line x^1-x^4 . Fig. 5 is a vertical section showing a different form of the invention.

The carbureter comprises a casing formed with an oil chamber 1, an air inlet chamber 2 and a mixing chamber 3, the chamber 2 being formed, for example, of a tubular member whose lower end is formed as a cap screwing on the top of and forming a cover 40 for the chamber 1, and said mixing chamber comprising a top member 3 screwing on member 2 and provided with an outlet 4 having means such as screw threads 5 for attachment to the inlet of suction means such as a gas engine, a throttle 6 being provided in said outlet 4. The tubular member 2 is provided with an inlet 7 communicating with the outer air and extending into an annular space 8 within the tubular member 50 and below a valve seat 9 on said member.

The valve is formed as an inverted frustoconical member 10 which is supported by its stem 11 working within a vertical tubular guide 12 on the member 2, in such manner that the conical face of the valve member 10 contacts with the valve seat 9 to control the

passage of air from the air space 8 to the mixing chamber 3. The stem 11 of the valve 10 is formed with an internal well chamber 15 substantially closed at the top by a partition wall 16 and partially closed at the bottom, a tubular projection 17 extending downwardly from the bottom of the stem and communicating with the interior of the well chamber and with a valve chamber 18 below said well chamber, said valve chamber being formed in a boss 19 extending up from the bottom of the oil chamber 1. A valve member preferably formed as a needle valve 21 and provided with an operating thumb piece 22 enters the lower end of this tubular projection 17 to control the passage of oil from the valve chamber 18 into the well 15, said valve chamber 18 communicating with the oil chamber through a duct 23. The needle valve 21 fits loosely in the thumb piece 22, as shown in the drawing, so as to be capable of a slight lateral movement to enable it to adjust itself to the nozzle formed by the open lower end of the tubular projection 17. A constricted passage 24 is provided around tubular member 17 to allow a retarded flow between chamber 18 and the interior of tubular guide 12, giving the effect of a dash pot.

Stem 11 has an annular channel 20 communicating with the oil chamber through an opening 13 in the wall of the tubular guide 12, this channel being full of oil and serving as a liquid seal to prevent air being drawn down between the stem and the guide during periods of violent suction.

The partition wall 16 at the top of the well 15 is provided with a minute aperture 25 for the purpose hereinafter stated, and an aspirator tube 26 extends through said partition wall nearly to the bottom of the well 15 and near to the upper end of the valve member 10, said valve member being formed with an open topped chamber or recess 28 around this tube and with a plurality of passages 29 extending from the lower portion of the valve member into said recess to establish communication from the air space 8 to said recess directly around the tube 26.

Valve 10 is formed with a recess 27 extending upwardly in its conical portion around the tubular guide member 12 and around the stem 11 of the valve, the lower portion of the conical valve member 10 surrounding the upper portion of the tubular

member 12 and telescoping thereon. This construction protects the sliding joint between the tubular member 12 and the valve stem from being fouled and clogged by dust or dirt carried in with the inlet air.

Suitable means are provided for maintaining a definite level of oil in the chamber 1, said means consisting, for example, of an annular float 30 surrounding the tubular 10 guide 12 and controlling a lever 31 mounted in a lateral extension 32 of the oil chamber and carrying a valve portion 33 controlling the outlet of the oil supply pipe 34, so that when the level of the oil falls below the required height in the oil chamber, the valve 33 will be open to admit a further supply of oil. A conduit or tube 36 leads from the mixture chamber 3 to the upper part of oil chamber 1, and is provided with a valve 37, whereby the pressure in the oil chamber 20 may be regulated. Oil chamber 1 has a small opening 38 to the outer air, to allow air to enter in restricted quantity.

The operation is as follows: The throttle 25 6 being open, and the engine being set in operation, each suction stroke of the engine will produce a condition of suction within the mixture chamber 3 causing the valve 10 to be lifted and allowing air to flow from 30 the inlet 7 through the annular space 8 and between the valve member 10 and its seat into the mixture chamber 3. When the engine is at rest, the oil will flow from the oil chamber 1 through a duct 23 into the valve 35 chamber 18, and the regulating valve 22 is so adjusted that when the valve member 10 is fully depressed sufficient clearance will be left between the needle valve 21 and the tubular projection 17 to enable the oil to 40 flow from the valve chamber 18 into the well 15 until it reaches the level of the oil in the oil chamber 1. When the engine is started up, the suction produced in the mixture chamber 3, as above described, causes a 45 condition of suction in the tube or oil communicating means 26 and causes the oil to be drawn up through said tube 26 into the mixture chamber. At the same time, the suction in the mixture chamber causes air 50 to pass through the ducts 29 into the recess 28 around the tube 26, the air thus delivered around the tube 26 passing upwardly in the recess 28 and carrying away the gasoline as fast as it is drawn from the tube 26, thereby 55 preventing gasoline from spattering on the top of the valve member 10 and insuring complete vaporization of the gasoline. As the oil is sucked up through the tube 26 in this manner the oil level is lowered in the 60 well and eventually the amount of oil passing through the tube is regulated by the adjustment of the valve member 21, which permits just sufficient oil to pass through at each lift of the main valve 10 to provide for 65 one charge. The well 15 is for the purpose

of providing an extra supply of oil in starting and after an operation is well under-way the suction of oil proceeds mainly directly from the chamber 18 through the tubular projection 17 without dependence on the 70 supply in the well, but when the engine is stopped, the oil rises in the well to furnish a supply for the next starting. In this operation, the minute aperture 25 at the top of the well permits escape of the contained 75 air or vapor as it is being displaced by the rising oil, it being understood, however, that when the engine is producing suction, the pressure remains greater in the well or 80 chamber 15 than in the tube 26, for the reason that the auxiliary air passages 29 maintain approximately atmospheric pressure within the recess 28, but said recess is too small to affect the condition of suction in the mixing chamber or in the tube 26, and 85 when the engine is started up the condition of suction in the mixing chamber is not immediately communicated to the interior of the well, and the gasoline is therefore immediately drawn up through the tube 26 by 90 reason of the difference in pressure at the inside and outside of the tube. Regulation for minimum oil supply is effected by controlling member 21, and for maximum supply by valve 37.

The feature of auxiliary air supply into a recess surrounding the oil aspirator, so as to take up the oil from the aspirator may be employed independently of the means for producing initial flushing. Such construction is shown in Fig. 5, wherein the oil chamber 40 and mixture chamber 43 with the inlet 44, outlet 45 and throttle 46 are substantially as above described, but the valve member 50 is formed simply with an 100 internal passage 48 continuous with the tubular extension 49 for co-operation with the valve member 50, said valve member 50 being provided in its upper end with a recess 51 into which extend the auxiliary air passages 52 from the air space 53 communicating with the air inlet 44 and the aspirator tube 55 communicating with the central passage 48 in the valve member 50. The passage 48 extends upwardly within this recess above the points 105 of communication with the said auxiliary air passages, so that the auxiliary air entering said recess and passing upwardly therein carries away and vaporizes the gasoline, 110 as the gasoline leaves the aspirator.

What I claim is:

1. A carburetor comprising a casing provided with an oil chamber, a mixing chamber having an air inlet and an outlet, a throttle in said outlet, said mixing chamber being between the said inlet and throttle, an air controlling valve movably mounted in the casing to control communication between the air inlet and the mixing chamber, said valve having a stem slidable vertically 130

in the casing, said stem having an interior chamber and formed with an oil inlet at its lower end communicating with said interior chamber in the stem, an oil controlling valve member coöperating with said inlet to control supply of oil from the oil chamber to the chamber within said stem, and oil communicating means communicating with the said chamber within the stem 10 and with the mixing chamber.

2. A carbureter comprising a casing provided with an oil chamber, a mixing chamber having an air inlet and an outlet, a throttle in said outlet, said mixing chamber 15 being between the said inlet and throttle, an air controlling valve movably mounted in the chamber to control communication between the air inlet and the mixing chamber, said valve having a stem slideable vertically in the casing, said stem having an interior chamber and formed with an oil inlet at its lower end communicating with said chamber in the stem, an oil controlling valve member coöperating with said inlet 20 to control supply of oil from the oil chamber to the chamber within said stem, and oil communicating means communicating with the said chamber within the stem and with the mixing chamber, said oil controlling 25 valve member being adjustable to vary the amount of oil supply.

3. In a carbureter, a casing provided with an air inlet and an outlet, a mixing chamber between said inlet and outlet, oil supply 30 means, a valve member mounted to move vertically in the casing, and having a valve portion controlling communication of air from the inlet to the mixing chamber and formed with a passage communicating with the oil supply, valve means for coöperating with the lower end of said passage to control the oil supply, a tube communicating with said passage and open at its upper end to discharge into the mixing chamber, said 40 valve member being formed with a recess surrounding said tube and with passages communicating with said recess and with the air inlet to supply air in the recess around the tube, as above set forth.

4. In a carbureter, a casing provided with an air inlet and an outlet, a mixing chamber between the air inlet and outlet, oil supply means, a valve member mounted to move in the casing and having a valve portion 50 controlling communication of air from the inlet to the mixing chamber, a tube carried by said valve member and communicating with the oil supply and open at its upper end to discharge into the mixing chamber, 55 said valve member being formed with a recess surrounding said tube and with passage means establishing communication from the air inlet to said recess to supply air into the recess around the tube for the 60 purpose set forth.

5. In a carbureter, a casing provided with a mixture chamber, air inlet means, an oil chamber, and a valve controlling communication from said air inlet means to said mixture chamber, said valve being vertically 70 movable, and provided with a passage opening at the upper part of the valve for establishing communication from the oil supply means to the mixture chamber, said valve being movable in response to the suction in the mixture chamber to control the admission of oil thereto, an outlet means for said mixture chamber, and a throttle in said outlet means.

6. In a carbureter, a casing provided with 80 a mixture chamber, air inlet means, an oil supply means, a valve controlling communication from said air inlet means to said mixture chamber, and provided with a longitudinal passage for establishing communication from the oil supply means to the mixture chamber, said valve being movable in response to the suction in the mixture chamber to control the admission of oil thereto, and a longitudinally adjustable 85 member coöperating with said passage in said valve to control passage of oil therethrough, an outlet means for said mixture chamber, and a throttle in said outlet means.

7. In a carbureter, a casing provided with a mixture chamber, air inlet means, an oil chamber, a valve controlling communication from said air inlet means to said mixture chamber, and provided with a passage for 100 establishing communication from said oil chamber to said mixture chamber, said valve being movable in response to the suction in the mixture chamber to control the admission of oil thereto, and a longitudinally adjustable member coöperating with said passage in said valve to control admission of oil therethrough, said longitudinally adjustable member being mounted to move laterally within said passage to adjust itself 105 thereto, an outlet means for said mixture chamber, and a throttle in said outlet means.

8. In a carbureter, a casing provided with a mixture chamber, air inlet means and an oil chamber, a tube extending within said casing, a valve controlling communication of air from said air inlet means to said mixture chamber, said valve having a stem 115 slidably mounted in said tube, said valve and valve stem being formed with a passage communicating at its lower end with the oil chamber, and communicating at its upper end with the mixture chamber, and a needle valve adjustably mounted in the 120 bottom of the casing, and coöperating with the lower end of said passage to control supply of oil therethrough, an outlet means for said mixture chamber, and a throttle in 125 said outlet means.

9. In a carbureter, a casing provided with a mixture chamber, air inlet means and an oil chamber, a tube extending within said casing, a valve controlling communication of air from said air inlet means to said mixture chamber, said valve having a stem slidably mounted in said tube, said valve and valve stem being formed with a passage communicating at its lower end with the oil chamber, and communicating at its upper end with the mixture chamber, and a valve adjustably mounted in the bottom of the casing, and coöperating with the lower end of said passage to control supply of oil therethrough, said tube being provided with means for admission of oil thereto, and said valve stem working as a piston therein, whereby the tube serves as a dash pot for the valve, an outlet means for said mixture chamber, and a throttle in said outlet means.
10. In a carbureter, a casing provided with a mixture chamber, air inlet means and an oil chamber, a tube extending within said casing, a valve controlling communication of air from said air inlet means to said mixture chamber, said valve having a stem slidably mounted with a passage communicating at its lower end with the oil chamber, and communicating at its upper end with the mixture chamber, said tube being provided with means for admission of oil thereto, and said valve stem working as a piston therein, whereby the tube serves as
- 5 a dash pot for the valve, an outlet means for said mixture chamber, and a throttle in 35 said outlet means.
11. In a carbureter, the combination with the mixing chamber and air inlet means of a valve controlling communication from said air inlet means to said mixing chamber, 40 said valve having a stem and a recess around said stem, and a tubular guide fitting said stem and extending upwardly into said recess.
12. In a carbureter, the combination with 45 the mixing chamber and air inlet means of a valve controlling communication from said air inlet means to said mixing chamber, said valve having a stem and a recess around said stem, and a tubular guide fitting 50 said stem and extending upwardly into said recess, said valve having a nozzle at the lower end of the valve stem, and said valve having passage means establishing communication between said nozzle and the 55 mixing chamber, oil supply means in communication with said nozzle and a valve coöperating with said nozzle to control such communication.

In testimony whereof, I have hereunto set 60
my hand at Los Angeles, California, this
21st day of October, 1909.

ALFRED C. STEWART.
